ROTARY REFINER

Edmund P. Arpin, Jr., Neenah, Wis., and Raymond P. Frye, Chicago, Ill.; said Frye assignor to said Arpin

Application July 7, 1948, Serial No. 37,338

11 Claims. (Cl. 92—26)

1

This invention relates to improvements in rotary refining machines which are used to refine wet, fibrous material, such as pulp, paper stock and the like. More particularly the present invention has to do with improvements in rotor mountings and to improved means for adjusting the rotors relative to the cooperating refining surfaces of the stationary abrasive shell within which the rotors are rotated.

For most efficient operation of a rotary refiner, it is necessary that the rotors be securely mounted in their housing in such a way that they can be easily and quickly inserted or removed from the housing. It is also desirable that means be provided for positively maintaining a clearance between the rotor stone and the abrasive cylindrical wall relative to which they rotate and, further, that mechanism be provided for quickly and easily adjusting the clearance.

In accordance with our present invention each rotor stone is positively held in a housing or backing plate by means of a plurality of adjustable wedge-shaped members which are securely held in place by bolts. A pressure pad disposed between the rotor stone and several wedge members assures a uniform application of pressure on all parts of the rotor stone, thus minimizing the possibility of stone rupture or uneven wearing of the stone surface.

A minimum operating clearance is always provided between the surface of the rotor element and the surface of the abrasive lining of the shell by means of a simple lever fulcrumed in a hollow box-like housing secured to the central hollow shaft of the rotor refiner, having one end disposed in an aperture in an upstanding ear portion of the backing plate and the other end arranged for contact with a radially-extending pin which extends into the interior of a hollow shaft which constitutes the rotor shaft. Wedge-like members movable within the hollow shaft are externally operable to force the radially-extending pins outwardly and thus limit the amount of minimum clearance provided between the cooperating surfaces of the rotor element and the abrasive lining of the shell.

Our novel construction further provides a threaded clamping member associated with the longitudinal rod connected to the wedge-like members for adjusting each rod longitudinally in the hollow shaft in accordance with the markings on a calibrated dial. While each rod may be adjusted individually in the hollow shaft, provision is also made in the present invention to shift as a unit the platform on which all the

2

clamping units are assembled and thus simultaneously adjust all the rods longitudinally in the hollow shaft. The calibrated dial method of individually adjusting each rod, and therefore each set of rotors in the hollow shaft, is obviously a great advantage since an accurate record of the clearances between the rotor stone and the abrasive lining can be kept without checking the clearance itself by opening up the casing of the rotary refining machine. The provision for adjusting all of the individual adjusting mechanisms as a unit provides a means whereby after an original adjustment of the rotor clearances, subsequent adjustments may be quickly and accurately made by moving the entire unit.

It is therefore an important object of the present invention to provide a mounting for a refining element in a rotary refiner assembly which may be quickly and easily removed from or inserted into the backing plate of the rotor assembly without disturbing adjacent rotor assemblies and which provides means for quickly and easily adjusting the rotor in place.

A further object of this invention is to provide a rotor refiner comprising a stationary shell having a cylindrical abrasive liner and a rotor including centrifugally acting rotor elements having abrasive surface for cooperation with the abrasive lining to bring about the desired refining action and wherein an externally operable clamping device carrying calibrated means is associated with an internal lever mechanism for accurately adjusting the minimum clearance between the associated rotor elements and the abrasive lining.

It is a further important object of this invention to provide a rotary refiner comprising wedge-like members movable within a hollow shaft, each wedge-like member being arranged to adjust the clearance between a set of associated rotor elements and the abrasive lining of the machine and wherein all wedge-like members disposed in the rotor refiner may be adjusted longitudinally of the machine simultaneously from a point exterior of the machine.

Other and further important objects of this invention will be apparent from the disclosures in the specification and the accompanying drawing.

On the drawing:

Figure 1 is a longitudinal elevational view of a rotary refiner embodying the principles of our invention with parts broken away and in section, and with other parts in elevation.

Figure 2 is a fragmentary vertical sectional

view taken substantially on the line II—II of Fig. 1 with parts in elevation.

Figure 3 is a fragmentary vertical sectional view taken substantially on line III—III of Fig. 2.

Figure 4 is an elevational view of the end of the rotary refiner of the present invention wherein the novel unitary adjusting means of this invention is disclosed.

Figure 5 is a fragmentary vertical sectional view taken substantially on line V—V of Fig. 1.

Figure 6 is a fragmentary horizontal sectional view taken substantially on line VI—VI of Figure 4.

Figure 7 is a fragmentary enlarged sectional view of a portion of the adjustment mechanism shown in Fig. 1.

Figure 8 is a fragmentary vertical sectional view taken on line VIII—VIII of Figure 4.

In Fig. 1, the reference numeral 10 indicates generally a rotary refiner embodying the principles of our invention, including a generally cylindrical shell or casing 11 defining a support structure which is supported normally in horizontal condition upon suitable supports 12. The shell 11 is provided with end plates 13 and 14, the end plate 13 at the inlet end of the machine and having an inlet opening 15, and the plate 14 at the discharge end having a discharge opening 16. Each end plate is outwardly dished and provided with a central boss 18 defining a central opening for receiving, in bearing relation, a hollow shaft 19. Said shaft 19 is adapted to be rotated centrally in the casing 11 by a grooved pulley 20. Disposed within the dished portion of the inlet end plate 13 and secured to the shaft is an impeller member 21 which receives the material as it enters the inlet opening 15 and directs it toward its periphery for subsequent passage between the working surfaces of the refining machine.

The shell 11 is provided internally with a liner 22, composed of a number of ring sections 23 which are formed of suitable abrasive material, such as stone, metal or a synthetic ceramic of an abrasive type.

As best seen in Fig. 2, a series of equally spaced helical grooves 24 extend longitudinally in the machine and form continuous passages along the inner surface of the ring sections 23.

The particular refining machine herein illustrated to disclose the novel rotor construction and mounting of the present invention includes rotor assemblies 25 pivotally mounted on a housing 29, in peripheral sets of four each, for rotation with the hollow shaft 19 to which a tubular central portion 33 is keyed. Each rotor assembly includes a refining element 27 secured in a backing plate 28 which has spaced upstanding ear portions 31, Fig. 3, which straddle flange parts 32 on the housing 29 and are pivotally mounted thereon by a pin 30. As the shaft 19 is rotated, the rotor moves outwardly by centrifugal force causing the refining element to coact with the abrasive surface of the liner ring 23 to refine the fibrous material as it is moved between the refining surfaces by the action of the impeller 21 and by the pressure head under which the material is delivered to the inlet opening. Both the liner ring 23 and the rotor element 27 may be formed of stone, metal or of a synthetic ceramic of an abrasive type.

A feature of the present invention is the provision of a simple, positive acting linkage for maintaining a minimum clearance at all times between the surface of the refining element and the abrasive surface of the liner ring 23. This linkage

comprises a lever 35 pivotally mounted at central hub portions 36, Figure 3, on a shaft 38 which is journaled in the flanges 32 of the housing 29. One end 35a of the lever 35 is disposed in an aperture 39 of an arm 40 integrally formed with the upper surface of the backing plate 28. The other end 35b of the lever 35 is disposed in abutting contact with the end of a push rod 42 slidably mounted in aligned radial apertures in the hollow shaft 19 in the housing 29.

As a means of controlling the radially inward and outward movement of the push rods 42 there is provided a series of frusto-conical wedge members 43, Fig. 1, secured to telescoping rods 44, 45 and 46 extending longitudinally inside the shaft 19. It will be noted in Fig. 1 that two wedge members 43 are secured to each rod. The position of each of the rods 44, 45 and 46 may be adjusted individually or they may be adjusted as a unit from the outside of the casing by means which will be described in detail hereinafter.

The inner end of each push rod 42 is in contact with the face of one of the wedge members 43 and, thus, the longitudinal positions in the shaft 19 of the members 42 determine the extent of outward pivoting of the rotor assemblies 25. A spring 48, Fig. 2, is disposed about the hub portion 36 of the rod 35 having end portions 49 resiliently urged into contact with the tubular portion 33 of the housing 29 and a roller equipped end portion 50 in contact with the face of the backing plate 28. This spring 48 prevents the rotor stone assembly 25 from dropping away from the ring 23 when the machine is shut down.

Further details of construction and operating of a refining machine to which our novel rotor construction and actuating means may be applied, may be had by reference to the copending application of one of us, Edmund P. Arpin, Jr., U. S. Serial No. 640,734, filed January 12, 1946, now issued as Patent No. 2,475,869.

Referring to Fig. 2, the backing plate 28 comprises a substantially flat central portion 52 with an overhanging ledge 53 which extends across the trailing end of the plate forming a heel against which the corresponding portion of the stone 27 is pressed when the rotor is assembled therein.

At both sides of the backing plate, a wall portion 55, Fig. 3, extends away from the flat central portion 52 to provide a recessed chamber 56 which is adapted to receive, in guiding relation, a strip 57 formed on the stone 27 to fit in the chamber.

An important feature of this invention is the provision of a novel means of securing the rotor stone 27 in the backing plate 28. As shown in Fig. 2, a metal pressure pad 59 is disposed across the leading edge of the rotor stone with a pad of cushioning material 60 between the surfaces of the pad 59 and the stone. This cushioning pad 60, which may be made of a material such as rubber, soft metal alloy or plastic, protects the stone surface under compression against metal surfaces. In this connection, a cushioning pad 61, Fig. 3, may be disposed between the rotor stone strip 57 and the backing plate 52 and also between the metal housing 11 and the various ring sections 23 which form the abrasive lining.

A series of wedges 62 are disposed between an overhanging ledge 63 at the leading edge of the backing plate 28 and the pressure pads 59. A stud bolt 65 is threaded at one end into each backing plate 28 and at the other end passes

freely through an opening in each wedge 62 for

threaded engagement with a nut 67. By tightening the nut 67 each wedge 62 may be forced inwardly to press the pressure pad 59 against the rotor stone and firmly urge it into place in the backing plate 28.

It is therefore seen that there is provided in this invention a novel wedge means for adjustably securing a rotor stone in a backing plate. Since this novel wedge means is disposed at the outer periphery of the rotor each refining element may be removed from or inserted into the backing plate without disturbing the adjacent rotor assemblies in the refining machine. Further, the pressure pad 59 which extends across the width of the refining element provides means for uniformly distributing the pressure exerted by the clamping means on the refining element.

The means provided in this invention for adjusting the longitudinal position of the conical shaped wedge members 43 in the hollow shaft 19 comprises separate clamping assemblies 70, 71 and 72, Figure 1 for each of the telescoping rods 44, 45 and 46 respectively. Each of these clamping assemblies includes a collar 73, Figure 4 having a base portion 74 secured to a platform 75 which has side flanges 76 overhanging a stationary table-like frame member 77, fixedly attached as a part of the support structure shell 11, on which the platform is slidably disposed. One side of the collar 73 is open, providing abutting arms 78 and 79 which may be drawn together by bolts 80.

In Fig. 8 it is seen that the clamping assembly 70 also comprises a threaded body member 82 on which may be integrally formed or suitably secured the rod 44. The collar 73 is internally threaded to receive the body member 82 which has a flanged end portion 83 arranged to abut one end of the collar 73 to limit longitudinal movement of the threaded body member 82. A series of holes 85 are provided in the periphery of the end portion 83 into which a bar 83a may be inserted for rotating the member 82 in the stationary collar 73 and thus moving the member 82, the connected rod 44 and the associated cone-shaped wedges 43 longitudinally in the hollow shaft 19. It will be understood, of course, that when an adjustment is being made, the bolts 80 will be threaded outwardly in the arms 78 and 79 to relax the grip of the collar 73 on the body member 82.

In order to coordinate the settings of the wedges 43 in the shaft 19, a calibrated arm 86, Figure 8 is secured to the upper surface of each collar assembly, extending axially of the threaded body member 82 with a free end portion 86a overhanging a calibrated ring 87 rotatably mounted on an annular shoulder 88 of the body member 82. A plurality of cap screws 89 are threaded into the member 82 against a washer 90 which overlaps the edge of the calibrated ring 87. When the washer 90 is threaded tightly against the ring 87, the ring will be secured to the member 82 for movement therewith.

The arm 86 may be calibrated so that one full revolution of the member 82 will cause the longitudinal movement thereof a distance equal to one division mark on the arm. The ring 87 may be calibrated in any suitable part of a revolution, as for example eight divisional parts, as shown in Fig. 5.

Each of the clamping assemblies 70, 71 and 72 are identical except for the provision in the threaded body member of the assembly 72 for free longitudinal passage therethrough of rods 44 and 45 and the provision in assembly 71 for

free longitudinal passage therethrough of rod 44.

The threads in the body member of each assembly have identical pitches so that equal rotation of each member will cause equal longitudinal movement of the associated rod in the hollow shaft 19. Thus, in Fig. 8, if the flanged end 83 is in a position for abutting the collar 73, the edge 87a of the ring 87 is aligned with the first division mark, indicated by reference numeral 93, on the arm and the zero mark, Fig. 5, on the face of the ring 87 is aligned radially with the edge of the calibrated arm 86. Subsequent rotation of the body member 82 away from the initial setting will then be recorded by the longitudinal and radial movement of the ring 87.

As previously mentioned, each of the collars of the three clamping assemblies is secured to a platform 75, which is slidably mounted on a stationary base 77. This platform can be secured to the base 77 by drawing a longitudinal strip 91 up tightly against the lower surfaces 77a of the base 77 and 75a of the platform 75 which are disposed in flush relation at either side of the base 77.

It is a special feature of this invention that the platform 75 can be adjusted bodily relative to the frame for simultaneously adjusting all the rods 44, 45 and 46 mounted thereon. This is accomplished by means of a disk 96 disposed in an aperture 97 of a substantially rectangular configuration on the platform 75. The disk 96 is eccentrically secured to the end of a rod 98 which is journaled for rotation in a passage 99 extending downwardly through a depending arm 100 of the platform 75. The lower end of the rod 98 is secured, as by a pin 102, to a rotatable socket member 103 which has a slot 104 adapted to receive a bar 105 for rotating the eccentric disk. It will be apparent from Figs. 6 and 7 that rotation of the disk will cause reciprocating longitudinal movement of the platform 75 and the clamping assemblies mounted thereon.

From the foregoing description it is seen that there is provided in this invention novel threaded means for separately adjusting each rod longitudinally of the hollow shaft 19 and an eccentric means for adjusting all rods in the rotary refiner simultaneously. Each of these methods of adjustment represents a distinct advance in the art since they afford for the first time means for accurately adjusting rotor clearance, for keeping a record of the clearance of any one set of rotors and for comparing at a glance the clearances of all sets of rotors.

It will, of course, be understood that various details of construction may be varied through a wide range without departing from the principles of the present invention, and it is, therefore, not the purpose to limit the patent granted hereon otherwise than necessitated by the scope of the appended claims.

We claim as our invention:

1. In a rotary refiner for wet fibrous material, a rotor assembly comprising a backing plate including a recessed portion defined by marginal flanges and having threaded passageways adjacent the leading edge thereof, a stone refining element movable into said recessed portion against said flanges having a generally arcuate processing surface and a flat surface extending across the leading edge, a pressure pad positioned against said flat surface, a plurality of wedge members disposed between said pressure pad and a flange of said backing plate and having passageways therethrough in alignment with the

passageways in said backing plate, threaded studs projecting through the passageways in said wedges for engagement in the threaded passageways of said backing plate, and nuts on said studs for exerting pressure on said wedge members.

2. In a rotary refiner for wet fibrous material, a stationary shell having a cylindrical abrasive liner, a hollow drive shaft, centrifugally acting rotor elements movable against said abrasive liner, members secured to said shaft, pins carried by said members for pivotally mounting the leading portions of said rotor elements, levers pivotally mounted intermediate their ends on said members and having free end portions, rods associated with one end of each lever and extending radially through said hollow shaft, an arm portion projecting from each of said elements and having an aperture for receiving the other end of each of said levers, and wedge means in said hollow shaft associated with the radially inward end of each rod for controlling the amount of clearance between said rotor and said cylindrical shell.

3. In a rotary refiner including a support structure, a hollow shaft rotatable in said structure and secured against longitudinal movement relative thereto and a plurality of telescoping rotor-adjusting rods movable longitudinally of said shaft, apparatus for simultaneously adjusting all of said rods longitudinally in said shaft comprising a platform having a slot therein and being slidably mounted on said support structure, threaded collar members secured on said platform, a threaded member secured to each rod and in threaded engagement with one of said collars and eccentric means journaled in said support structure and engageable in the slot in said platform for shifting said platform longitudinally of said shaft.

4. In a rotary refiner including a support structure, a hollow shaft rotatable in said structure and secured against longitudinal movement relative thereto and a plurality of telescoping rotor-adjusting rods movable longitudinally in said shaft having threaded end portions extending out of said shaft, apparatus for adjusting all of said rods simultaneously longitudinally in said shaft comprising a platform slidably mounted on said support structure, and threaded collar members secured on said platform, one of said collars being in threaded engagement with the end portions of each rod.

5. In a rotary refiner including a support structure, a stationary shell having a cylindrical abrasive liner, a hollow shaft rotatable in said structure and secured against longitudinal movement relative thereto, centrifugally acting rotors movable against said abrasive liner, flanges extending radially outwardly from said hollow shaft, pins carried by said flanges for pivotally mounting the leading portions of said rotors, levers pivotally mounted intermediate their ends on said flanges and having free end portions, rods associated with one end of each lever and extending radially through said hollow shaft, an arm portion projecting from each of said rotors and having an aperture for receiving in positive abutting relations with one wall thereof of the other end of each said levers, wedge means in said hollow shaft associated with the radially inward end of said rod for controlling the amount of clearance between said rotor and said abrasive liner, a rotor-adjusting rod connected to said wedge means and having a threaded end and movable longitudinally in said hollow shaft,

and means for adjusting said rod in said shaft for actuating said wedge means to control the clearance between the rotors and the abrasive liner including a threaded collar mounted on the support structure for engagement with the threaded end portion of said rod and means for rotating said threaded portion to move said rod longitudinally in said shaft.

6. In a rotary refiner including a support structure, a hollow shaft rotatable in said structure and a plurality of telescoping rods movable longitudinally of said shaft, apparatus for simultaneously adjusting all of said rods longitudinally in said shaft comprising a platform slidably mounted on said support structure, threaded collar members secured on said platform, a threaded member secured to each rod and in threaded engagement with one of said collars, and means journaled in said support structure and engageable with said platform for shifting said platform longitudinally of said shaft.

7. In a rotary refiner for wet fibrous material including a support structure, a stationary shell having a cylindrical abrasive liner, a hollow shaft rotatable in said structure, centrifugally acting rotors movable against said liner, flanges on said hollow shaft, pins carried by said flanges for pivotally mounting the leading portions of said rotors, levers pivotally mounted intermediate their ends on said flanges and having free end portions, rods associated with one end of each of said levers and extending radially through said hollow shaft, means on each of said rotors engaging the other end of each of said levers, wedge means in said hollow shaft associated with the radially inward end of each of said rods for controlling the amount of clearance between the corresponding rotor and said abrasive liner, a rotor-adjusting rod movable longitudinally in said hollow shaft and connected to said wedge means and having a threaded end, and a fixed threaded collar cooperating with said threaded end for adjusting said rod in said shaft and thus actuating said wedge means.

8. A rotary refiner comprising a support structure, a hollow shaft rotatable in said structure, a plurality of telescoping adjusting rods movable longitudinally in said shaft having end portions extending out of said shaft, means cooperating with said end portions for adjusting each rod in said shaft independently of said other rods, and apparatus for simultaneously adjusting all of said rods, said apparatus including a platform slidably mounted on said support structure and means carried by said support structure for moving said platform.

9. In a rotary refiner for wet fibrous material, a rotor assembly comprising a backing plate including a recessed portion defined by marginal flanges and having a leading edge and a trailing edge, said backing plate having a threaded passageway adjacent one of said edges, a stone refining element disposed in said recessed portion and seated against one of said marginal flanges and having a generally arcuate processing surface and a flat surface extending across said one edge, a pressure pad positioned against said flat surface, a plurality of wedge members disposed between said pressure pad and the other marginal flange of said backing plate and having passageways therethrough in alignment with the passageways in said backing plate, threaded studs projecting through the passageways in said wedges and engaged in the threaded passageways of said backing plate, and nuts

on said studs for exerting pressure on said wedge members.

10. In a rotary refiner for wet fibrous material, a stationary shell having a cylindrical abrasive liner, a drive shaft, centrifugally acting rotor elements movable against said abrasive liner, members secured to said shaft, pins carried by said members for pivotally mounting the leading portions of said rotor elements, levers pivotally mounted intermediate the ends thereof on said members and having free end portions, an arm portion projecting from each of said elements and having means for receiving one end of each of said levers, and means operatively associated with the other end of each lever for effecting pivotal movement of the lever to control the amount of clearance between said rotor and said cylindrical shell.

11. A rotary refiner comprising a support structure, a hollow shaft rotatable in said structure, a plurality of telescoping adjusting rods movable longitudinally in said shaft having end portions extending out of said shaft, means cooperating with said end portions for adjusting each rod in said shaft independently of the other of said rods, apparatus for simultaneously adjusting all of said rods longitudinally in said shaft comprising a platform having a slot therein, said platform being slidably mount-

ed on said support structure, threaded collar members secured on said platform, a threaded member secured to each rod and in threaded engagement with one of said collars, and eccentric means journaled in said support structure and engageable in the slot in said platform for shifting said platform longitudinally of said shaft.
